UNITED STATES PATENT OFFICE.

FREDERIC T. DE LONG, OF CHICAGO, ILLINOIS, AND ARTHUR W. HAWKINS, OF MUSKEGON, MICHIGAN, ASSIGNORS TO CHICAGO RAILWAY EQUIPMENT COMPANY, OF CHICAGO, ILLINOIS, A CORPORATION OF ILLINOIS.

BRAKE-BEAM SUPPORT.

Application filed August 31, 1922. Serial No. 585,509.

To all whom it may concern:

Be it known that we, FREDERIC T. DE LONG and ARTHUR W. HAWKINS, citizens of the United States, residing at Chicago, Illinois, and Muskegon, Michigan, respectively, have invented a certain new and useful Improvement in Brake-Beam Supports, of which the following is a full, clear, and exact description, such as will enable others skilled in the art to which it appertains to make and use the same, reference being had to the accompanying drawings, forming part of this application.

Our invention relates to railway rolling stock and consists in an improved third or fourth point support for brake beams.

The general object of our invention is the usual one of providing against dropping of the beam upon the rail, and the special objects of our invention are to combine a safety guard with means which maintain the inclination of the beam with respect to the wheels irrespective of wear on the brake shoes and wheel tires, and to provide a brake release.

In the accompanying drawings which illustrate a selected embodiment of our invention and a number of modifications—

Figure 1 illustrates a preferred form and shows the spring plank of a truck and the brake beam in section with our improved support applied thereto.

Figures 2 to 8 illustrate modifications which will be referred to later.

Our support consists essentially of two pieces, one to be mounted upon the brake beam 1 and the other to be fixedly carried by the truck and preferably mounted upon the spring plank 2. In Figure 1 the beam element is indicated as a strip 3, preferably of spring material and enclosing one or more of the brake beam members, but of whatever material or how secured to the brake beam, extending downwardly and rearwardly beneath the spring plank.

The spring plank member 4 essentially consists in an inclined bearing for element 3 and in the preferred form comprises a combined flat and roller bearing. Member 4 is shown as having flat surfaces 5 spaced from each other and inclined to correspond to the inclination of element 3 and aligned with these surfaces are the adjacent sides of

rollers 6 rotatably mounted upon one or more flanges 7 formed on member 4 integrally with surfaces 5. Member 4 is secured to the spring plank by bolts 8 and 9 which pass through suitable flanges provided on the member. A bolt 9 is used for the horizontal flange to make possible its removal and the retraction or insertion of shims such as 10 which are placed beneath the corresponding flange of member 4 and the spring plank to adjust the angle of inclination of the bearing surface.

Element 3 extends beyond the rear of member 4 far enough to accommodate and seat a compressed spring 11, the other end of which is seated against the face of member 4. This spring yieldingly resists the application of the brakes and serves to release the brakes when the air pressure in the brake cylinder is released. The spring construction of member 3 yieldingly resists rotation of the brake beam about its axis. In this form, roller 6 dissipates most of the friction produced by reciprocal movement of the element 3 and bearing surfaces 5 serve largely to guide the element.

In Figure 2 a modification is shown in which element 12, corresponding to element 3 in Figure 1, is rigid and slotted at 13 so as to be mounted upon a single roller element 14. In this form, the yielding resistance to rotation of the beam is provided by a spring 15 which also serves as a guide for element 12 corresponding to the surfaces 5 of member 4 in Figure 1.

In Figure 3, an end roller supporting bearing 16 is shown, the other element of the bearing consisting of an adjustable shoe 17 which may be adjusted vertically by a set screw 18 provided with a lock nut 19. In this form, the spring plank member is rigidly secured to the spring plank. In this construction the brake beam element 20 consists of one piece enclosing the compression member 21 of the brake beam and may be either flexible or rigid according to whether or not it is intended to accommodate the rotation of the brake beam.

In Figure 4 the brake beam and spring plank members are combined in a single strip of flat spring-like material having a return bend formed therein whereby the strip crosses itself at 22, the vertical portion

being slotted to receive the inclined brake beam supporting portion. A helix 23 may be formed in the member to increase its elasticity. In this form, both rotation of the brake beam and brake setting travel of the latter are yieldingly resisted.

In Figure 5 the beam element 24 is shown as positioned above the compression member of the beam but extending downwardly and rearwardly through a slot in the vertical portion of a spring plank member 25 which extends above the upper surface of the spring plank and is bent back over the spring plank to provide a sliding bearing 15 for the beam element 24. It will be understood that the parts may be inverted without affecting their operation, although various circumstances may make the upper position of the support preferable to a sub-20 spring plank construction an example of which is shown in Figure 6 in which the element 26, embracing the compression member of the beam, extends downwardly and rearwardly from the lower edge of the beam. 25 The spring plank member 27 has a hooked portion 28 engaging the flange of the spring plank and a bearing portion 29 just under the spring plank. In both of these forms the element secured to the brake beam may 30 be either yielding or rigid although the yielding form is preferred.

Another modification is shown in Figure 7 in which the beam element 30 is rigid and the spring plank member 31 is yielding. 35 Element 30 extends through an elongated slot in member 31 and only supports the beam element at one extreme of the latter's travel, but yieldingly resists turning movement of the beam at all times.

40 In the construction shown in Figure 8 the beam member 32 does not serve to support the brake beam but its engagement with the underside of the spring plank, whether the latter is provided with an additional bearing member or not, will prevent rotation of the brake beam upon its axis and assure the even application of the brake shoe to the wheel, irrespective of the thickness of the shoe or the diameter of the wheel. Beam element 32 may be either rigid or of spring 45 material depending on whether or not the guide is intended to be yielding.

Various other modifications will suggest 50 themselves to those familiar with the art and will be produced in the commercial development of our invention and we contemplate all such as fall within the scope of the appended claims.

60 We claim:

1. A brake beam support comprising a member to be secured to the truck spring plank, and an element to be secured to the brake beam and slidably mounted in said member.

65 2. A brake beam support comprising a

member to be secured to the truck spring plank, and an element to be secured to the brake beam, to extend downwardly and rearwardly therefrom, and to be slidably mounted in said member.

70

3. A brake beam support comprising a member to be secured to the truck spring plank and provided with an inclined bearing and an element to be secured to the brake beam and mounted to slide on said bearing.

75

4. A brake beam support comprising a member to be secured to the truck spring plank, and a yielding element secured to the brake beam and slidably mounted in said member.

80

5. A brake beam support comprising a member to be secured to the truck spring plank, and an element rigid lengthwise and yielding transversely of its length and mounted in said member to slide longitudinally of its length.

85

6. In a brake beam support, an inclined element secured to the brake beam, and a fixed member in which said element is mounted to slide in the direction of its inclination.

90

7. In a brake beam support, an inclined element secured to the brake beam, and fixed bearings for said element spaced longitudinally of the axis thereof in which said element is slidably mounted.

95

8. In a brake beam support, an inwardly and downwardly inclined element secured to the brake beam, and a member to be mounted on the truck spring plank provided with a bearing for said element, said element and member being adapted to yieldingly resist rotation of the brake beam.

100

9. In a brake beam support, an inwardly and downwardly inclined element secured to the brake beam, a member to be mounted on the truck spring plank, provided with a bearing for said element, said element and member being adapted to yieldingly resist rotation of the brake beam, and means for yieldingly resisting the application of the brake.

105

10. In a brake beam support, an inwardly and downwardly inclined element secured to the brake beam, and a member mounted on the spring plank provided with bearings spaced transversely of said element and receiving the latter between them.

110

11. In a brake beam support, an inwardly and downwardly inclined element secured to the brake beam, and a member mounted on the spring plank, provided with a pair of rollers spaced transversely of said element and receiving the latter between them, and a guiding surface cooperating with said 125 roller bearings to position said element angularly.

120

12. In a brake beam support, an element which embraces the brake beam and has a downwardly and rearwardly inclined arm,

130

and an element mounted on the truck spring plank and providing a similarly inclined bearing for said first-mentioned member.

13. In a combined brake beam support 5 and release, a bracket on the truck spring plank, a beam engaging member slidably mounted in said bracket, and means yieldingly thrusting said member toward one end of its sliding movement in said bracket.

10 14. In a combined brake beam support and release, a bracket on the truck spring plank, a beam engaging member slidably mounted in said bracket and extending rearwardly therefrom, and a spring compressed 15 between said bracket and the rear end of said member.

15. In a brake beam support, an element extending downwardly and rearwardly from the brake beam, and a member 20 mounted upon the spring plank and comprising cooperating flat and roller bearings for said element.

25 16. A brake beam support comprising a member to be secured to the truck spring plank and provided with an inclined bearing and an element to be secured to the brake beam and mounted to slide on said bearing, and means for adjusting the inclination of said bearing.

30 17. In combination with a brake beam and a truck, a member secured to the brake beam extending downwardly and rearwardly therefrom beneath a fixed element carried by the truck, having sliding engagement

with said element and adapted to maintain 35 a predetermined relative angle between the beam and the wheel to which it is applied.

18. In combination with a brake beam and a truck, a member of yielding material 40 secured to the brake beam and extending downwardly and rearwardly therefrom beneath a fixed element mounted on the truck, the upper face of said member having sliding engagement with the underside of said element whereby tilting of the beam about 45 its axis is yieldingly resisted.

19. In combination with the brake beam and spring plank of a truck, a member secured to the brake beam and extending toward the spring plank, and a pair of rollers 50 mounted on the spring plank and spaced transversely of said member and adapted to receive the latter between them.

20. In a brake beam, a downwardly and rearwardly extending element adapted to contact with a fixed truck element to maintain 55 a predetermined inclination of the beam.

21. In a brake beam, a downwardly and rearwardly extending element adapted to 60 contact with a fixed flexible truck element to yieldingly maintain a predetermined inclination of the beam.

In testimony whereof we hereunto affix our signatures the 10th and 8th days of 65 August, 1922, respectively,

FREDERIC T. DE LONG.
ARTHUR W. HAWKINS.
